ARTIFICIAL RESPIRATION AND
ASPIRATION APPARATUS

Morris Dann, Cleveland, Ohio

Application December 26, 1941, Serial No. 424,515

4 Claims. (Cl. 128—29)

This invention relates to apparatus for artificial resuscitation and aspiration, and novel means of controlling the devices used in artificial respiration and artificial aspiration.

At the present time, there are many different methods of effecting artificial respiration, sometimes called resuscitation, and included in these methods is the manual method. In this manual method, there is not any certain way of controlling the pressure that is externally applied to the person requiring resuscitation, and in some cases the lungs are in such a collapsed condition that mere external application of pressure is not sufficient to effect respiration. Any lack of skill on the part of the person administering the resuscitation or inability to continue application of manual resuscitation will be seen to prevent the actual desired result, wherein artificial resuscitation is necessitated. Even in manual method of resuscitation, it is generally necessary to have a certain amount of equipment to properly complete the renewal of respiration in the patient.

Mechanical means of one kind or another have been contemplated, and the well known "iron lung" so-called, is an example of the type of artificial respiration apparatus heretofore devised. Of course, the "iron lung" is limited in certain ways because it is expensive and difficult to transport from one place to another, and is only in certain cases used to effect artificial resuscitation as such.

Further methods have been contemplated whereby oxygen is introduced through the respiratory tract in some form and by certain means, but no adequate method of control of the introduction of the oxygen has been heretofore contemplated. Of course, it is seen that where uncontrolled use of oxygen is employed, the artificial resuscitation is no more effective than by not actually attempting to resuscitate the person. Necessarily, in many cases, it is necessary as an accompanying adjunct to the artificial resuscitation method, to remove certain obstructions from the respiratory tract, such as for instance in new born babies, the mucous formations, or in certain instances, in various types of illnesses in adults or children, similar mucous formations are present and are necessary to be removed.

The present methods of aspiration of foreign liquids in respiratory tracts have not previously been very greatly experimented with, and, generally, heretofore, involved the insertion on the part of a physician, or other competent person,

of one end of a catheter tube at the source of foreign liquid or mucus, and then inserting the other end in the mouth of the physician, and by manual vacuum created in the tube, to withdraw the mucus. Of course, a trap is commonly inserted in the catheter tube line between the source of foreign liquid or mucus, and the physician's, or other person's mouth, to collect the mucus.

In view of the foregoing recitation of the general field to which this invention is directed, the objects of this invention are to provide adequate means of applying artificial respiration or resuscitation, whereby the apparatus for accomplishing these results will be portable, simple to manufacture, relatively inexpensive, and accomplish the resuscitation in a minimum of time, and with a minimum of danger for the person to whom the artificial respiration is being applied.

A further object of this invention is to enable the operator of the apparatus to very closely control the administration of oxygen, and at the same time, have the actual administration performed in an automatic manner.

A further, and more particular object of this invention is to provide apparatus that will be operated by the source of oxygen being administered to the patient in order to prevent any possibility of explosion where the apparatus is used in an ether filled room, or where other explosive fumes are present.

A still further object of this invention is to provide a manometer control means whereby the manual control of the administration of oxygen is augmented by an automatic control eliminating in many cases the element of human error which prevents effectual artificial resuscitation.

This automatic control provides a safety feature for the resuscitation apparatus that is wholly new in this art.

A still further and more particular object of this invention is to provide a novel form of apparatus to carry out the aspiration of foreign liquids in the respiratory tract prior to application of artificial respiration.

Another object of this invention is to provide apparatus that is comprised of relatively few working parts and prevent contamination of any of the parts by the liquid withdrawn from the patient to which the respiratory apparatus is applied.

Further and more particular objects of the invention will be understood upon reference to the drawings, in which:

Figure 1 is a general view showing the mounting of the aspirator and respirator units in connection with a suitable oxygen tank on a movable carriage.

Figure 2 is a detail sectional view of the manometer control means.

Figure 3 is a detail sectional view looking about on the line 3—3 of Figure 2.

Figure 4 is a detail view of the pressure motor and associated connections with certain portions of the mechanism broken away.

Figure 5 is an end view of Figure 4, showing the general outline of the air motor unit and location of various parts.

Figure 6 is a detail sectional view of a portion 15 of the air motor unit taken about on the line 6—6 of Figure 5.

Figure 7 is a detail view of the aspirator unit with certain portions shown in section, and other parts broken away, showing the relationship of 20 collecting means and air motor unit.

Respirator unit

Referring to the drawings, in Figure 1 the numeral 1 designates generally a carriage or carrier for the apparatus and 2 indicates a tank of conventional form adapted to contain oxygen. The numeral 3 indicates a shut-off valve located on the oxygen tank, and 4 a volume valve associated therewith, which is of conventional form and used in a conventional manner, as associated with storage tanks for compressed gases in general. The number 5 generally designates an air type motor and control unit, 6 a respiratory mask of conventional form connected with the motor 5 by a suitable tubing 6a. The numeral 7 indicates a manometer control unit generally indicated thereby and located adjacent the motor unit aforesaid. The numeral 8 indicates, as a whole, the aspirator actuating unit, and 9 the aspirator unit indicating and receiving receptacle, or more simply, a trap. 10 is the catheter tube with the trap 9 aforesaid, 11 a main supply line from the oxygen tank 2 to the air motor unit 5, to supply the oxygen thereto and supply oxygen as controlled by the motor unit to the respirator mask. 12 indicates a supply line whereby oxygen is supplied to the aspirator unit 8 and associated mechanism.

The carriage 1 is made up to be carried by suitable rubber tired wheels 13, connected to a tubular frame, which, for the purposes of this invention, is made up of one piece of tubing and formed with the upright members 16 connected by a transverse tubular section 17 at their upper portions, and having at the lower ends thereof tubular members 18, extending rearwardly from the pivots of the wheels 13, and downwardly extending tubular sections 19 adapted to receive any conventional form of casters 15.

The rearwardly extending arms 18 are suitably held by a triangular shaped platform 20 comprised of a rear rectangular member 21 connected with triangular side members 20, and having a rectangular bottom portion 14 serving as a bottom platform for support of the oxygen tank 2.

Adjacent the upper tubular member 17 which serves as a handle to propel the carriage 1, and disposed between the arms which connect the upright members 16, with the transverse member 17, is a platform 22, which supports the air motor unit 5, said motor unit 5, in turn, being supported by triangular members 24, which are connected to the platform 22 in any suitable manner.

A tubular member 25 connects the lower plat-

form 20 with the upper platform 22 and serves as a bracing means for the carriage 1 and also as a mounting member for the aspirator unit 8, which may be fastened to this upright tubular member 25 in any suitable fashion. A drawer 23 is slidably mounted in any suitable way on the under side of the upper platform 22, and is furnished for storage and carrying of spare parts for the apparatuses.

The platform 22 serves as a mounting member for the manometer control unit, generally designated as 1, by means of threaded portions 26 of the manometer unit frame and located generally between the respirator unit 5 and the adjacent tank 2.

Referring more particularly to Figure 4, for the construction of the motor unit 5, and associated control and supply mechanism, the unit 5 comprises an outer shell 28 of a tubular form with substantially round end member 29 which receives the open end 28 of the respirator unit 5, in an annular groove formed therein, and fastened thereto in a conventional manner. The other end 31 is also generally of round configuration and also is located on the opposite open end of the tubular shell 28 which is adapted to be received in an annular groove 32 and likewise fastened thereto by suitable means.

It is to be understood that in the mechanism, generally to be described, and heretofore described parts, that are exposed to atmospheric conditions and operate in the atmosphere, are coated with a suitable metallic coating which will prevent corrosion and permit a certain amount of sterilization.

The substantially round end member 31 has a mechanism housing 33 integrally cast therewith, and extending therefrom.

The motor generally indicated at 34 operates in a conventional manner and is adapted from a vacuum operated windshield wiper motor of conventional design, to act as pressure motor.

United States Patent Reissue No. 15,502 granted December 5, 1922, illustrates such a windshield cleaner motor of the conventional design illustrated.

One end of the cylindrical casing 35 is suitably fastened substantially centrally to the end member 31, by means of bolts 37 adapted to be received by a flange portion 38 of the cylindrical casing 35, and threadedly engaged with the end member 31. Fitted in the cylindrical casing 35 are piston members 39 and 39' connected by a piston rod 40. A connecting passage 41, cast in the cylindrical housing 35, is adapted to alternately connect air chambers formed by the pistons 39 and 39', and the cylindrical casing 35, as permitted by suitable valve mechanism.

A sliding valve member 43, which provides gradual cut-off and admission of oxygen, is adapted to reciprocate in the housing 33, when the pistons 39 and 39' are actuated by oxygen entering the chambers A and B. The valve 43 is connected to the piston unit 39—40—39' by means of female threaded portion 44, the piston 39' being engaged by a male threaded portion 45 of the valve 43. Intermediate the ends of the valve 43 is a tapered portion 46, best seen in Figure 6, whereby the oxygen is gradually admitted to the patient and gradually cut-off from the patient, as will be more particularly described hereinafter. The valve portion 46 forms a valve chamber 46a in the casing 33.

A passage 47 formed in the housing 33 is the means by which oxygen from the storage tank 2,

passing through the conductor 11 connected by an adaptor 53 having a threaded member 54 to engage a complementary threaded opening of the casing 33 aligned with a connecting passage 55 and chamber 56 in which the needle valve 48 operates, enters the chamber 46a formed by the valve 43 in open position. Suitably adjustable in the passage 47 is the needle valve 48 with the threaded stem portion 49 operating in the threaded screw portion 49' of the casing 33 and operable by a handle or knob means 50 to regulate the volume of flow of oxygen around the tapered portion 46 of the valve 43 to the outlet passage 51, and by this passage, to an exhaust and inhalation chamber or passage 52 for purposes to be described.

The chamber 52 in the casing 33 serves as a passage for the entrance of oxygen to the large chamber C formed by the casing 48 of the air motor unit, and thence to the respirator mask by means of a passage 57 in the end member 31, to which is connected an adaptor 58 by suitable means, and on which the respirator tube 6a has been placed. Likewise, at certain times, the chamber 52 serves as a passage for the used oxygen to the atmosphere, through the passage 59 and to the outlet 60 on which a perforated cap 33a is placed, when the valve 43 has moved to the left from its position in Figure 6 far enough to permit the flow of the used oxygen through the passages 52 and 59 when the valve 43 has moved sufficiently to open this passage 60 to passage 59.

The conduction of oxygen for operation of the motor 34 is effected by means of the passage 61 connected with the chamber 56 in which needle valve 48 operates. Aligned with the opposite end of passage 61 is a threaded connecting adaptor 62, with which metal tubing 63 is connected by a slip nut 64, the tube 63 connected at its other end to a by-pass adaptor 65 by a similar slip nut 66. Intermediate the slip nut 66 and threaded connection of adaptor 65 with the end member 31, is a by-pass opening 67. Control of oxygen entering the by-pass tube 68, and thus control of speed of movement of the piston unit 39-40-39', is effected by a needle valve of conventional form controlled by a knob or handle 69 adjacent the end member 31. A by-pass tube 68 conveys oxygen to act on the piston means 39 to move the piston 39 to move valve 46 to the right as seen in Figure 4.

Connected to the adaptor 58 adjacent the tube 6a which is connected with the respirator mask 6, is the manometer line 27, whereby the manometer unit 7 is placed in the circuit of the oxygen in its passage from the motor unit 5 to the mask 6 for purposes to be later set forth.

The manometer control unit, generally indicated 7, in Figure 2, is of special construction, and comprises a bottom plate 72 of generally square configuration having an indented portion 73 therein, adapted to receive the closed lower end of a glass tube or vessel 74 of relatively great length as compared with its diameter, said tube formed near its upper end with an enlarged portion 75.

The upper end of the tube 74 is closed by a top plate 76 which is adapted to receive the end of the tube in an annular groove 77 positioning the tube 74 in the device in cooperation with the indentation 73 in the lower plate 72. Tie rods 78, having suitable head portions 78a, pass through the upper plate 76 and the lower plate 72, and by means of the threaded ends 26, position the unit as a whole, and firmly maintain the unit

on the upper platform 22 of the carriage 1. The tube or vessel 74 is open to the atmosphere through the passage 79 in a filling and venting member 80 suitably fixed in the top plate 76.

5 A U-shaped glass indicator tube 81 of small diameter is so formed that it generally conforms to the inner surface of the glass vessel 74, but spaced somewhat therefrom, one end 82 suitably held in an adaptor 83, said adaptor 83 being threadedly engaged with a suitable threaded opening in the upper plate 76 and at the outer end engaged to the supply tube 27 by a slip nut 84, whereby pressure at the respirator mask 6 is the same as the pressure in the tube 27 and the glass tube 81.

The indicator tube 81 is formed with a curved portion at the end 85, adapted to direct water forced from the end of the tube 81 in the course of operation of the respirator unit, against the enlarged section 75 of the vessel 74, to prevent splashing of the water which would interfere with visibility of the level of the liquid in the indicator tube 81. An opening 86 in the wall of the tube 81, and properly spaced from the end of the tube, 85, below the surface of the water in the vessel 74, provides a filling opening for the indicator tube 81 after said tube has been partially emptied by pressure directed thereto by means heretofore described.

30 A graduated scale 87 formed from suitable non-corrosive material, is adapted to be supported by suitable means, as wires 88, on the indicator tube 81, as shown in Figures 2 and 3, and in such a position, that the scale of the apparatus laid out thereon is visible to the operator of the respirator unit. The scale 87 will be preferably of a length to provide for the indication of pressure from zero to twenty five centimeters of water in view of the fact that present day knowledge teaches that a high of twenty two centimeters of water in a tube of suitable cross section indicates the maximum pressure human lungs can withstand. Of course, it is understood that a proper scale could likewise be laid out where mercury or other liquid 40 is the indicating medium, in cooperation with some other measuring graduation suitably calibrated.

45 For the purposes of this invention, however, water is used as a measuring medium, and the scale 87 is lined in for centimeters, the water level corresponding with the zero reading of the scale 87, when the apparatus is not operating and at certain times in the operation of the respirator unit.

55 From the foregoing, it will be readily seen that pressure oxygen being furnished to the respirator mask 6 will be measured by a displacement of the water in the indicator tube 81, and the exact pressure may be observed by comparison of the level of the water in the tube 81 with the graduated scale 87 coordinated therewith.

60 It is also apparent that any excessive pressure above that desired to be administered through the respiratory mask 6 would be at least partially allowed to escape through this previously described connection of respirator mask tube 6a with manometer control unit supply tube 27, through the indicator tube 81, thence to the atmosphere through the opening 85 of the tube 81 and the vent 79 of the vessel 74.

65 Under certain conditions where the use of the manometer unit 7 in the circuit is not desired, a shut-off valve 71 of conventional construction, see Figure 6, is provided.

70 The purpose of the manometer unit 7 is, there-

fore, seen to be to control the pressure and to indicate the pressure of the oxygen administered to the patient by the operation of the respiration apparatus, but primarily the manometer unit 7 is used as a safety device to permit the escape of excess pressure transmitted to the respirator mask 6, as before described, and this connection and unit used in this manner are believed to be wholly new in the art of artificial resuscitation.

Aspirator unit

The aspirator unit, previously generally referred to as being comprised of an aspirator unit actuating mechanism 8, indicating and receiving receptacle or trap 9 and the catheter tube 10, is mounted on the tubular carriage member 25 in any suitable manner, and is more particularly illustrated in Figure 7, wherein a cylindrical shell 89, adapted to be closed by substantially circular end members 90 and 91, is shown in section.

An annular recess 92 in the end member 91 engages one end of the shell 89, and a similar recess, not shown, of the end member 90, engages the other end of the shell 89, and these are held in position by suitable bolts 93 and 94, which engage portions of the working mechanism of the unit located substantially centrally of the shell 89. The connection of the bolts 93 and 94 with the end closure members 90 and 91 is likewise seen to support the mechanism of the unit within the shell.

A boss formed on an angular fitting 103 is designated at 102, and is adapted to form a threaded connection for the bolt 94 to the part 90. Pressure motor 95, similar to that used in the respirator mechanism before described, is comprised of a cylindrical casing section 96; cup-shaped end section 97 fitted with an air tight joint to the section 96, and containing similar valve mechanism to that before referred to, is used in this apparatus likewise.

The end opposite the cup-shaped member 97, which encloses the valve mechanism, is connected to a vacuum pump generally indicated at 98 by suitable bolts 99 adapted to be received by the flange portion 100 in a mating flange portion 101 of the pump 98. Other details of the mechanism of this motor 95, that are the same as previously described in connection with the motor of the respiratory unit, will not be further enumerated.

Oxygen for actuation of the motor 95 is furnished from the storage tank 2, through the hose 12 to an adaptor 104, suitably mounted in the shell 89, and by means of the tube 105, which is in turn controlled through the needle valve 106 of conventional construction, by a handle 107, thence to the angular fitting 103 of the cap 97 by the tube 108. The needle valve 106 is suitably mounted in the shell or casing 89 so that a knob or handle 107 is accessible to the operator for adjustment of the speed of reciprocation of the piston unit by regulation of the valve to allow more or less oxygen to be used to actuate the piston 118, and piston 117.

A vacuum pump, generally designated as 98 and of somewhat conventional construction, similar to that used in automobiles to pump the fluid from the storage tank to the carburetor or other fuel mixing means, is associated with the previously described motor and is comprised of an upper casing or body member 109, and a lower substantially cup-shaped member 110 having a bottom 110a.

The upper casing or body member 109 and lower casing 110 are connected together in alignment by means of bolts 111, suitably engaged with

the flange member 112 on the upper casing 109 and threadedly engaged with a flange member 113 with the lower casing 110. A flexible membrane or diaphragm 114 is adapted to have its periphery engaged by the respective flange members of the aforesaid casing members and between those flange members thus forming a chamber or so-called vacuum chamber E above the diaphragm 114. The upper chamber or vacuum chamber E is closed by a cap member 115 secured to the upper casing 109 by means of the bolt 93, previously described, which engages a cross member 116 attached to the outer end of the casing member 109 at its ends.

15 The diaphragm 114 is operable by means of a piston rod 117, which is secured at one end in the piston member 118 by a threaded engagement therewith, in a manner similar to the connection of the previously described valve member 43 to the piston 39' of the respirator air motor 34. The piston rod 117 is adapted to reciprocate in connection with the piston 118 in a similar manner to the previously mentioned valve member 43. The piston rod 117 is engaged with the diaphragm 114 by means of nuts 120 and 121. Entrance of air into the lower chamber formed by the diaphragm 114 and the cup-shaped body member 110 is effected by means of an opening 122 in a side wall of the casing 110 to prevent any pressure or 20 vacuum formation in this chamber, which will be designated D.

25 A check valve 123, which provides escape of air on the up-stroke of the piston rod 117 and adapted to close on the down-stroke thereof, is associated with the upper casing in any suitable manner, and is of a somewhat conventional form. The check valve 123, when in a closed position, provides the means of effecting a vacuum in the chamber E, which is transferred through a similar check valve 124, to the aspirator collecting unit or trap 9, which is connected to the vacuum pump 98 by a tubing 125 threadedly engaged with the pump and engaged with the outer shell 89, as by means of collars 126 and 127.

30 45 The tubing 125, being of rigid construction, is adapted to engage with a special cap 128, which forms an air tight seal with the glass bottle 129 of the trap member 9 by means of a passage 130 in the cap 128, which is connected with and aligned with the tube 125, whereby the vacuum created 50 in the chamber E of the vacuum pump 98 is transferred to the bottle 129.

40 55 A glass tube 131 in the bottle 129 is suitably held in engagement with the special cap 128 by an adaptor 132 and so disposed as to bring the open end 133 of the tube 131 proximate the bottom of the bottle 129. A passage 143 in the cap 128 is aligned with the upper end of the tube 131 and in turn aligned with a threaded adaptor 135 60 having a suitable air passage therein, which in turn is connected to the catheter tube 10, in any suitable manner, whereby the vacuum, in the bottle 129 formed by the pump 98, is transferred to the catheter tube, and liquid or mucus withdrawn 65 from the patient, to whom the catheter tube has been applied, will be drawn through the tube and be collected in bottle 129.

70 75 The foregoing arrangement of bottle and glass tube located therein does not permit the mucus or other foreign liquid being withdrawn, to come in contact with the pump.

A clearer understanding of the pump and associated mechanism of this portion of the invention, and the manner in which it is operated, will be brought out in a description of the operation

of the aspirator unit now following, in which the operation of the respirator unit and its associated mechanism, will at first be described.

Operation of apparatus

The respirator mask 6, having been first placed over the mouth and nose of the patient and suitably held in engagement therewith, the valves 3 and 4 of the storage tank 2 are opened. The valve 50 is then opened, permitting oxygen to act on the piston unit 39-40-39', causing reciprocation thereof, and thus reciprocation back and forth of the slide valve 43 connected thereto. The valve 69 is then opened, permitting the oxygen from the storage tank 2 to be directed toward the respirator mask 6, as described hereafter.

Oxygen is permitted to enter the respirator mask tube 6a, as the valve surface 46, around which the chamber 46a of the valve mechanism is formed, gradually opens when moving from left to right. The alignment of the passages 47 and 51, and their connection, is thus effected by the chamber 46a, formed by the valve surface 46, and oxygen thus enters the passage 52, thence proceeds to the opening 57 aligned with the respirator mask tube 6a. This action takes place as the valve 43 is carried back and forth by the motor piston. The shape of the valve surface 46 causes the introduction of oxygen to the respirator mask, as before described, in a gradual manner, because of the conformation of this surface, whereby a gradual introduction of oxygen is accomplished, and the maximum amount is admitted when the valve surface 46 is in its full right position, as exemplified somewhat in Figure 6, and then gradually cuts off admission of oxygen when the valve 43 on which the tapered surface 46 is located, until it is entirely cut off in a full left position of the valve member 43.

This action is seen to be constant, and even, with complete control over the volume of oxygen admitted and variation of the speed of operation seen to be obtainable.

As the valve 43 approaches its maximum left position, atmospheric pressure on the patient's lungs effects the collapse of the lungs and forces the contents thereof back through the respirator mask tube 6a and through the passages 52 and 60, of the respirator unit, thence to the atmosphere.

The manometer control unit 7, connected to the line 6a, of the respirator mask 6, is seen to be alternately actuated during the course of operation of the respirator air motor unit. That is, the fluid in the indicating tube 81 is forced out when oxygen is admitted by the slide valve 43 of the motor unit 5, and the exact amount of pressure applied may be observed by the operator of the apparatus and controlled by the means 50 and 69, in accordance with the pressure, as shown on the scale 87, of the manometer control unit 7.

It is well known that the capacity of lungs of individuals vary, and thus, in view of certain standards set up for approximate pressure, which various persons are able to withstand, and somewhat in accordance with the age and other factors, the manometer control unit 7 registers accurately the actual pressure, and if for some reason the setting of the speed and volume controls, and the amount of oxygen admitted by the valve 43 is too great for the person receiving artificial respiration, the excess pressure, and consequently some oxygen associated in the course of administering this pressure, will be relieved from the

patient through the escape of the oxygen and relief of the pressure from the end 85 of the tube 81 and to the atmosphere by bubbling through the liquid in the manometer vessel 74, and forcing the liquid out of the indicator tube 81. Upon release of the pressure or escape, as the case may be, it is obvious that the manometer control unit 7 is automatically conditioned, and reset to again receive and disclose the pressure of operation.

10 The foregoing description will show that the operator of the mechanism or apparatus is enabled by careful observation to adjust the needle valves 50 and 69 in accordance with the demands of the patient, and the capacity of the lungs and other factors apparent to those who will use the apparatus.

15 The conditions under which artificial respiration may be effected are subject to variance, and factors, such as stoppage of the trachea or parts 20 of the passages of the throat must be overcome, and in order that any mucus restriction or other foreign liquid restriction in these passages can be removed the aspirator apparatus heretofore 25 specifically described has been constructed by means of which the artificial aspiration is administered.

A description of the operation of the aspirator unit just previously described, as to detail parts and certain functions, will be seen to more clearly 30 illustrate the cycle of operation, and is as follows:

The catheter tube 10 of conventional construction and generally composed of material of a rubber fabric or type, is inserted at the point where the mucus, or other substance, is located, 35 and the valve 107 of the aspirator unit 8 is opened, and thus the motor 95 is started into operation by the pressure of oxygen entering the cylinder chambers at the ends of the piston members, as for instance, piston member 118, as alternately 40 permitted to do so by the valve mechanism located in the cap 97.

Movement of the piston unit causes a flexing 45 of the diaphragm 114, and on the down-stroke of the piston creates a vacuum in the chamber E of the vacuum pump 98, which is transmitted by the tubular connection 125 to the interior of the glass receptacle or trap member 129, and hence through the glass tube 131 to the catheter tube 10 and thus draws the mucus, or other 50 liquid, from the patient into the bottle 129 and collects it there.

It is understood that the bottle 129 may be of 55 convenient size to hold a quantity of withdrawn liquid. It is, of course, obvious that the bottle 129 may be unscrewed from the cap 128 and the liquid collected by the previously mentioned means may be suitably removed therefrom.

The actual rate of withdrawal of the liquid 60 from the patient will, of course, depend upon the speed of the piston 118, and the amount of vacuum created in the vacuum pump 98 will depend on that speed; the foregoing mentioned speed and volume of vacuum may be controlled by opening or closing the valve 107.

65 Having thus described my invention, what I claim as new and desire to secure by Letters Patent of the United States, is:

1. In resuscitation apparatus of the class described, in combination, a source of supply of 70 oxygen under pressure, an instrumentality for administering the oxygen to a patient, passage means connecting the oxygen source to the said instrumentality, a valve chamber a valve in said chamber for controlling said passage means, said valve being formed to gradually open the

passage means when the valve is moved to supply oxygen to the said administering instrumentality, a motor connected with said valve for operating the same, and means for venting the oxygen flowing to the administering instrumentality from the said passage means, when a predetermined resistance to the flow of oxygen from the said instrumentality is met with.

2. In resuscitation apparatus of the class described, in combination, a source of oxygen under pressure, an oxygen administering instrumentality for application to a person, passage means connecting the oxygen source with the said instrumentality, valve means in said passage means for controlling the quantity of oxygen supplied to the administering instrumentality through said passage means, means for operating the said valve means, a passage leading to the atmosphere and connected with the aforesaid passage means for venting oxygen from the latter when the flow of oxygen from the administering instrumentality meets with a predetermined resistance, said venting means comprising means for normally preventing the venting action of the venting means, and constituting an indicator for determining the pressure of the oxygen supplied to the passage means during the normal action of the administering instrumentality, and valve means to temporarily incapacitate the venting means independently of said resistance condition.

3. In resuscitation apparatus of the class described, in combination, a source of supply of oxygen under pressure, an instrumentality for

administering the oxygen to a patient, ~~passage~~ means connecting the oxygen source to the ~~said~~ instrumentality, a valve chamber, a valve in said chamber for controlling said passage means, said valve being constructed of tapered formation opposite to the passage means to gradually open the passage means when the valve is moved to supply oxygen to the said administering instrumentality, a motor connected with said valve for operating the same, and means for venting the oxygen flowing to the administering instrumentality from the said passage means, when a predetermined resistance to the flow of oxygen from the said instrumentality is met with.

4. In resuscitation apparatus of the class described, in combination, a source of oxygen under pressure, an oxygen administering instrumentality for application to a person, passage means connecting the oxygen source with the said instrumentality, valve means in said passage means for controlling the quantity of oxygen supplied to the administering instrumentality through said passage means, means for operating the said valve means, a passage leading to the atmosphere and connected with the aforesaid passage means for venting oxygen from the latter when the flow of oxygen from the administering instrumentality meets with a predetermined resistance, said venting means comprising means for normally preventing the venting action of the venting means, and valve means to temporarily incapacitate the venting means independently of said resistance condition.
